CLAIM

The ornamental design for an acromial prosthesis component for total shoulder prosthesis system, as shown and described.

DESCRIPTION

FIG. 1 is a rear perspective view of an acromial prosthesis component for total shoulder prosthesis system, showing my new design;

FIG. 2 is a top plan view thereof, the bottom view being substantially the mirror image thereof;

FIG. 3 is a front elevational view thereof;

FIG. 4 is a side elevational view thereof viewed from the right of FIG. 3;

FIG. 5 is a rear elevational view thereof;

FIG. 6 is a side elevational view thereof, viewed from the right of FIG. 5;

FIG. 7 is a vertical cross-sectional view thereof, taken on line 7—7 of FIG. 5.
